UNITED STATES PATENT OFFICE.

EDWARD J. DOBERSTEIN, OF BLUE ISLAND, ILLINOIS, ASSIGNOR TO GOODMAN MANUFACTURING COMPANY, OF CHICAGO, ILLINOIS, A CORPORATION OF ILLINOIS.

MINING MACHINE.

Application filed August 21, 1922. Serial No. 583,076.

This invention relates to improvements in kerf cutting mining machines and more particularly to that class of kerf cutting machines called over-cutting machines. More particularly, it relates to the "slabbing" type of overcutting machines. Such machines are usually mounted on wheels and supported on the mine track both while moving from place to place and while forming a kerf, and are provided with cutting mechanism adapted to be swung angularly so as to cut a kerf transversely of the mine track or at the sides thereof.

One of the principal objects of the present invention is to produce a simple and efficient machine of the class described, in which, for convenience in manufacture and operation, a conventional type of shortwall mining machine primarily designed for normal operation on the mine floor, is incorporated and utilized as the main power element of the overcutting machine. Other objects of my invention will appear from time to time as the description proceeds.

In carrying out my invention, the shortwall machine with its conventional cutter arm and underframe removed, is rigidly mounted on a wheeled truck. A cutting element is pivotally mounted at the forward end of this truck to swing in a horizontal plane, and is provided with elevating mechanism whereby the height of the cutting element may be adjusted so as to cut a kerf at various levels. The operative devices associated with the shortwall mining machine motor are connected by suitable mechanisms to perform the various functions of the machine, as will hereinafter more fully appear.

The invention may best be understood by reference to the accompanying drawings in which

Figure 1 is a side view of a mining machine constructed in accordance with my invention.

Fig. 2 is a top plan view of the machine shown in Fig. 1.

Fig. 3 is a large detail view in vertical cross-section taken on line 3-3 of Fig. 2.

Fig. 4 is a rear end view showing the operating mechanism of the machine.

Fig. 5 is a top plan view of the operating mechanism at the rear end of the machine with portions thereof broken away.

Referring to the drawings, 10 indicates a

body portion of the truck, supported on axles 11, 11, provided with wheels 12, 12. The body portion may be of any suitable construction for the purpose, as for instance, it may comprise a channel frame member 13 provided with a top plate 14 forming a support for the mechanism mounted thereon. 15 indicates the main body portion of a shortwall mining machine which is mounted on the rear end of the truck as shown in Figs. 1 and 2. The shortwall machine is of the type provided with draft devices such as cables, chains or the like, and primarily designed to slide bodily along the ground during the cutting operation. Such mining machines usually have as common features, a main body portion, an underframe or shoe upon which it is supported, a cutter bar extending from beneath said body portion and provided with a cutter chain, and a vertically disposed driving shaft extending downwardly from said body portion and provided with a sprocket for driving the cutter chain. In adapting such a machine for use with my improved form of over-cutting machine, the ordinary underframe, the cutter arm and its cutter chain are removed, and the main body portion 15 of the machine is placed on and secured to the top plate 14 of the truck by suitable means such as bolts 18, 18. The driving shaft 16 extends through the top plate 14 and the sprocket 17 associated therewith, which normally engages the cutter chain, is arranged below said top plate, as clearly shown in Fig. 1.

The shortwall mining machine used to illustrate my invention is provided with a motor casing 20 containing a suitable motor such as an electric motor, having an armature pinion 22. An intermediate shaft 23 is geared to said armature pinion and carries thereon a bevel gear 24 and a worm 27. The chain sprocket 17 is driven from the bevel pinion 24 through the bevel gear 25 on shaft 16 and the clutch 26 (see Fig. 1) by which the driving connection between bevel gear 25 and the sprocket 17 may be engaged or disengaged at will.

As is well known to those skilled in the art, shortwall mining machines of this class are moved and controlled while on the ground by a suitable draft device or devices. In the machine illustrated herewith, two

sets of draft devices are provided comprising rope drums 30 and 31 mounted on the right and left sides of the machine respectively. This particular arrangement of draft devices forms the subject-matter of the co-pending application of Charles E. Davis, bearing Serial No. 374,476, filed April 17, 1920. Drums 30 and 31 are provided with flexible cables 32 and 33, as shown in Fig. 2. The main elements of the driving mechanism for drums 30 and 31 comprise the intermediate shaft 23 geared to the motor and provided with worm 27 as aforesaid, a worm gear 29, a variable speed mechanism 35 and an endwise movable shaft 36 driven by said variable speed mechanism and provided with interlocking clutches 37 and 38 on opposite ends thereof. The driving connection between clutch 37 and drum 31 comprises a shaft 39, driving pinion 40 and gear 41 on said drum. The driving connection between clutch 38 and drum 30 comprises a pinion 42, idler gear 43 and gear 44 on the latter drum. In the particular form of shortwall machine shown, ratchet devices are interposed between the gears 41, 44 and their respective drums 31 and 30, but inasmuch as these devices are not necessary when the shortwall machine is mounted on the truck, their details need not be described herein.

The variable speed mechanism 35 illustrated is preferably of the planetary type which may be of any approved construction, provided with an external friction band 50 and a friction adjusting handle 51 for the purpose of transmitting variable speeds to the shaft 36. Details of this transmission mechanism need not be described excepting to indicate a clutch member 52 feathered on the shaft 36 and provided with clutch jaws 53, 53, adapted to be engaged either with a high speed member 54 or a low speed member 55 of the planetary gear 35. The clutch member 52 is provided with a shifter yoke 56 and a control member 57 connected therewith. The endwise movable shaft 36 extends through the variable speed mechanism 35 and worm gear 29 to form an axial bearing therewith. The clutch member 37 comprises an annular flange 59 on one end of said shaft provided with clutch jaws 60, 60, adapted to engage with corresponding clutch jaws 61, 61, on the connecting shaft 39 extending to the left hand drum 31. The clutch 38 for connecting the shaft 36 with the right hand drum 30 is located adjacent the inner face of the pinion 42 on the right hand side of the machine. Said clutch comprises a sleeve 62 fixed to the shaft and extending through the pinion 42 to form an axial bearing therewith. Clutch jaws 63, 63, are carried by said sleeve and are adapted to engage corresponding clutch jaws 64, 64, preferably formed integral with the pinion

42. Means for shifting the shaft 36 comprises a shifter yoke 65 mounted on the sleeve 62 and provided with shifter arms 66, 66, which are operated by a suitable control handle 67. (See Fig. 4.) In the position shown in Figs. 4 and 5, the shaft 36 is in neutral position, that is to say, clutches 37 and 38 are both disengaged. It will be seen that if the control handle 67 is moved downwardly, the shaft 36 will be moved longitudinally so as to engage the clutch 37 to form a driving connection with the rope drum 31. On the other hand, if the control handle is moved upwardly, the shaft will be moved in the opposite direction, clutch 37 will be disengaged and the opposite clutch 38 will become engaged to form a driving connection with drum 30. By means of this interlocked arrangement of the clutches, only one drum may be driven at a time.

The rope drums are also provided with friction devices primarily designed to assist in the control of the shortwall machine when it is moved on the mine floor, but inasmuch as these retarding devices are not used when the mining machine is mounted on the truck, as in the present invention, their construction and use need not be described in the present application.

The manner in which the mechanism of the shortwall machine above described is utilized to perform various functions of the overcutting machine will hereinafter more fully appear.

Referring now to details of the cutting mechanism, it will be seen in Figs. 1 and 2 that a cutter arm 70 extends forwardly from a frame member 71 at the forward end of the truck 10. This frame member is mounted between a plurality of upright supports 72, 72, and arranged to move vertically therebetween by suitable elevating mechanism including a plurality of racks 73, 73, engaged by pinions 74, 74, on shafts 75, 75, carried by said frame member. Means for operating this elevating mechanism will hereinafter be described. The upright supports 72, 72, are mounted on a platform or turntable 76 pivotally supported on bed plate 14 of the truck body 10. In Fig. 3 it will be seen that this turntable is mounted on and secured to said bed plate by means of an annular ring 77 having an outwardly extending flange 78 along its upper portion. The turntable 77 has a downwardly extending rim portion 79 fitting over said annular member and provided with a plurality of bearing rollers 80, 80, placed about its periphery and extending inwardly to engage the periphery of the annular member 77 underneath the flange 78 thereof.

As heretofore described, the driving sprocket 17 of the shortwall machine is arranged below the plate 14 at the rear end

of the machine. Another sprocket 85 is mounted concentric with the turntable 77 in substantial horizontal alignment with the sprocket 17 and is connected therewith by means of a driving chain 86 which is substituted for the cutter chain which ordinarily is driven by sprocket 17. The front sprocket 85 has an elongated hub portion 87 extending upwardly therefrom and provided 10 with a pair of annular thrust collars 88, 89, arranged above and below a journal bearing 90 in said turntable. This journal bearing preferably comprises a split ring, of which one half is indicated at 90 in Fig. 3, to allow 15 removal of the sprocket 85 and associated parts. A chain sprocket 95 is mounted in the frame member 71 above the sprocket 85 and concentric therewith. A vertically disposed shaft 96 is connected to rotate with 20 sprocket 95. Said shaft extends downwardly from the latter sprocket and is feathered in the hub 87 of sprocket 85. The arrangement is such that the frame member 71 and the sprocket 95 carried thereby may be moved 25 vertically into various positions but yet have driving connection with the sprocket 85 at all times through shaft 96. The cutter chain 97 is engaged with and driven by the sprocket 95 in the usual manner.

30 The mechanism for raising and lowering the frame member 71 and cutter arm carried thereby comprises a gear 98 mounted on the hub portion of sprocket 95 and adapted to engage a pinion 99 on the stub shaft 100. A gear 101 is mounted on a second stub shaft 102 and is adapted to mesh with the pinion 99. Said gear is vertically movable on its shaft by means of a clutch collar 105, and has a downwardly extending cone 103 adapted 40 to be clutched with a worm 104 when gear 101 is in its lowermost position as shown in Fig. 3 and is in mesh with the pinion 99. Worm 104 drives a worm gear 106 mounted on transverse shaft 107. The latter shaft is 45 operatively connected to the longitudinally disposed shafts 75, 75, already referred to, by means of miter gears 108, 108. Pinions 73, 73, which engage the vertically disposed racks 72, 72, for raising and lowering the 50 cutting mechanism are mounted on these shafts as before described. The arrangement is such that when the gear 101 is meshed with pinion 99, the cone 103 engages the worm 104 to drive the shafts 107 and 55 75, 75. The motor of the machine may be reversed to raise and lower the cutting mechanism as desired. Worm 104 and worm gear 106 are of the "self-locking" type, that is to say, their pitch is such that the cutting 60 mechanism is maintained in any desired position.

Besides furnishing motive power for driving the elevating and cutting mechanism as above described, the mechanism of the short-wall machine performs other functions in

the operation of the overcutting machine. In the first place, either or both of the draft ropes associated with drums 30 and 31 may be utilized to rotate the turntable and the cutter arm carried thereby. This is accomplished by attaching one of the cables as for instance the cable 32 on the left hand drum 31 to a portion of the turntable 76 and then winding up the cable so as to rotate the turntable toward the rear end of the machine. One means of attaching the free end of the cable 32 is illustrated in Figs. 2 and 3, in which it will be seen that an eye 110 on the free end of said cable is connected to a pin 111 inserted through the periphery of 70 the turntable. It is obvious that the rope may be attached to the turntable in many other ways for the purpose of rotating the latter. The turntable may also be rotated in the opposite direction by several arrangements of the draft ropes. The shortwall machine is provided with a plurality of guiding sheaves 112, 112, at the forward end and 113, 113, at the rear end, which may be utilized to train the draft cables about 75 the machine in any desired manner. Means are also provided for locking the turntable 76 in predetermined positions with respect to the truck. For this purpose, the pin 111 already referred to may be used by removing a collar 116 countersunk in the surface of the turntable. The lower end of the pin may then be dropped into a suitable aperture 117 formed in the plate 14. A series of 80 such apertures may be provided so that the turntable and cutting mechanism may be locked in any position desired.

85 The draft mechanism may also be used for propelling the truck either forwardly or rearwardly when desired by anchoring one end of a cable, as for instance, the cable 33, in a fixed position at the rear of the machine, and winding in on the cable at any speed desired. This method of propelling the machine is particularly advantageous 90 for feeding the machine to the coal when it is making a "slabbing" cut along one side of the track.

95 Means for propelling the truck along the mine track through the medium of the truck wheels is provided by extending the right end 120 of shaft 36 which forms a driving connection to the drums 30 and 31 as already described. On this extension is loosely mounted a sprocket 121 in vertical alignment 100 with a sprocket 122 on the rear axle 11 of the truck. A driving chain 125 connects sprocket 121 and the sprocket 122. A clutch 124 affords an operative connection between 105 shaft 36 and sprocket 121. Both axles are 110 connected by a chain 126. By means of the driving mechanism just described, which is operated through the variable speed planetary transmission device 35, it will be seen 115 that the entire machine may be propelled 120

along the track at various speeds to transport it from place to place, or, under some conditions, to feed it to the coal.

An overcutting machine constructed as above described is capable of performing all of the ordinary functions of the so-called "slabbing" overcutting machine. That is to say, the cutter arm may be swung pivotally to make an arcuate cut at the front 10 or sides of the machine, or may be held at one side thereof to make an elongated or slabbing cut at one side of the machine as the latter is moved along the track, as already described. The cutter arm may also 15 be raised or lowered to cut at various levels. The means for operating the machine will readily be understood by anyone familiar with the use of machines of this class, from the foregoing detailed description of the machine.

I claim as my invention:

1. In a machine of the class described, a frame having supporting wheels, a cutting element comprising a projecting cutter bar 25 mounted at the forward end of said frame to swing about a substantially vertical axis, and a cutter chain for said cutter bar, in combination with coal cutting machine actuating mechanism of a conventional short-wall type primarily designed for operation 30 upon the mine floor, comprising an actuator, flexible draft means and cutter chain driving mechanism both operatively connected with said actuator through suitable gear reduction mechanism, said coal cutting machine having its cutter bar and cutter chain removed therefrom, and rigidly mounted on said frame in position to have its flexible draft means coact with said rotatably mounted cutting element to swing the latter about its axis, means affording a driving connection between said cutter chain driving mechanism and the cutter chain of said cutting element.
2. In a machine of the class described, a frame having supporting wheels, a cutting element comprising a projecting cutter bar mounted at the forward end of said frame to swing about a substantially vertical axis, and a cutter chain for said cutter bar, elevating means for moving said cutting element vertically respective to said frame, in combination with coal cutting machine actuating mechanism of a conventional shortwall type 50 primarily designed for operation upon the mine floor, comprising an actuator, flexible draft means and cutter chain driving mechanism both operatively connected with said actuator through suitable gear reduction mechanism, said coal cutting machine having its cutter bar and cutter chain removed therefrom, and rigidly mounted on said frame in position to have its flexible draft means coact with said rotatably mounted cutting element to swing the latter about its axis, means affording a driving connection between said actuator and said supporting wheels, and means affording a driving connection between said cutter chain driving mechanism and the cutter chain of said cutting element.
3. In a machine of the class described, a frame having supporting wheels, a cutting element comprising a projecting cutter bar mounted at the forward end of said frame to swing about a substantially vertical axis, and a cutter chain for said cutter bar, in combination with coal cutting machine actuating mechanism of a conventional shortwall type primarily designed for operation 60 upon the mine floor, comprising an actuator, flexible draft means and cutter chain driving mechanism both operatively connected with said actuator through suitable gear reduction mechanism, said coal cutting machine having its cutter bar and cutter chain removed therefrom, and rigidly mounted on said frame in position to have its flexible draft means coact with said rotatably mounted cutting element to swing the latter about its axis, means affording a driving connection between said actuator and said supporting wheels, and means affording a driving connection between said cutter chain driving mechanism and the cutter chain of said cutting element.

its axis, and means affording a driving connection between said cutter chain driving mechanism and the cutter chain of said cutting element.

3. In a machine of the class described, a frame having supporting wheels, a cutting element comprising a projecting cutter bar mounted at the forward end of said frame to swing about a substantially vertical axis, and a cutter chain for said cutter bar, elevating means for moving said cutting element vertically respective to said frame, in combination with coal cutting machine actuating mechanism of a conventional short-wall type primarily designed for operation 70 upon the mine floor, comprising an actuator, flexible draft means and cutter chain driving mechanism both operatively connected with said actuator through suitable gear reduction mechanism, said coal cutting machine having its cutter bar and cutter chain removed therefrom, and rigidly mounted on said frame in position to have its flexible draft means coact with said rotatably mounted cutting element to swing the latter about its axis, means affording a driving connection between said cutter chain driving mechanism and the cutter chain of said cutting element, and means operatively connecting said last named means with said elevating means.

4. In a machine of the class described, a frame having supporting wheels, a cutting element comprising a projecting cutter bar mounted at the forward end of said frame to swing about a substantially vertical axis, and a cutter chain for said cutter bar, in combination with coal cutting machine actuating mechanism of a conventional short-wall type primarily designed for operation 80 upon the mine floor, comprising an actuator, flexible draft means and cutter chain driving mechanism both operatively connected with said actuator through suitable gear reduction mechanism, said coal cutting machine having its cutter bar and cutter chain removed therefrom, and rigidly mounted on said frame in position to have its flexible draft means coact with said rotatably mounted cutting element to swing the latter about its axis, means affording a driving connection between said cutter chain driving mechanism and the cutter chain of said cutting element, and means operatively connecting said last named means with said elevating means.

5. In a machine of the class described, a frame having supporting wheels, a cutting element comprising a projecting cutter bar mounted at the forward end of said frame to swing about a substantially vertical axis, and a cutter chain for said cutter bar, in combination with a coal cutting machine of a conventional shortwall type primarily designed for operation 90 upon the mine floor,

comprising an actuator, flexible draft means and cutter chain driving mechanism both operatively connected with said actuator through suitable gear reduction mechanism, 5 said coal cutting machine having its cutter bar and cutter chain removed therefrom, and rigidly mounted on said frame in position to have its flexible draft means coact with said rotatably mounted cutting ele- 10 ment to swing the latter about its axis, means connected with and driven through the gear reduction mechanism of said draft means affording a driving connection between said actuator and said supporting 15 wheels, and means affording a driving connection between said cutter chain driving mechanism and the cutter chain of said cutting element.

6. In a machine of the class described, a 20 frame having supporting wheels, a cutting element comprising a projecting cutter bar mounted at the forward end of said frame to swing about a substantially vertical axis, and a cutter chain for said cutter bar, ele- 25 vating means for moving said cutting element vertically respective to said frame, in combination with coal cutting machine actuating mechanism of a conventional short- 30 wall type primarily designed for operation upon the mine floor, comprising an actuator, flexible draft means and cutter chain driving mechanism both operatively connected with said actuator through suitable gear reduction mechanism, said coal cutting ma- 35 chine having its cutter bar and cutter chain removed therefrom, and rigidly mounted on said frame in position to have its flexible draft means coact with said rotatably mounted cutting element to swing the latter about 40 its axis, means affording a driving connection between said actuator and said supporting wheels, and means affording a driving connection between said cutter chain driv- 45 ing mechanism and the cutter chain of said cutting element.

7. In a machine of the class described, a

frame having supporting wheels, a cutting element comprising a projecting cutter bar mounted at the forward end of said frame to swing about a substantially vertical axis, 50 and a cutter chain for said cutter bar, ele- vating means for moving said cutting element vertically respective to said frame, in combination with coal cutting machine actuating mechanism of a conventional short- 55 wall type primarily designed for operation upon the mine floor, comprising an actuator, flexible draft means and cutter chain driving mechanism both operatively connected with said actuator through suitable gear re- 60 duction mechanism, said coal cutting ma- chine having its cutter bar and cutter chain removed therefrom, and rigidly mounted on said frame in position to have its flexible draft means coact with said rotatably mounted 65 cutting element to swing the latter about its axis, means connected with and driven through the gear reduction mechanism of said draft means affording a driving con- 70 nection between said actuator and said sup- porting wheels, and means affording a driv- ing connection between said cutter chain driving mechanism and the cutter chain of said cutting element.

8. In a mining machine, a base, a turn- 75 table rotatably supported thereon and in- cluding an annular depending rim portion in supporting engagement with said base, a ring member removably secured to said base provided with an outwardly extending 80 flange within the inner face of said rim, and bearing rollers mounted in said rim portion having peripheral bearing on said ring be- 85 neath said flange and means affording lateral removal of said rollers from said rim to permit the latter to be withdrawn bodily in a vertical direction from said ring.

Signed at Chicago, in the county of Cook and State of Illinois, this 18 day of August, 1922.

EDWARD J. DOBERSTEIN.
